ATTORNEY

UNITED STATES PATENT OFFICE.

HENRY P. ROBERTS, OF NEW YORK, N. Y., ASSIGNOR, BY MESNE ASSIGNMENTS, TO DICTAPHONE CORPORATION, OF NEW YORK, N. Y., A CORPORATION OF NEW YORK.

ATTACHMENT DEVICE.

Application filed December 27, 1922. Serial No. 609,300.

To all whom it may concern:

Be it known that I, HENRY P. ROBERTS, a citizen of the United States, and a resident of the city of New York, county and 5 State of New York, have invented certain new and useful Improvements in Attachment Devices, of which the following, taken in connection with the accompanying drawings, is a specification.

This invention relates to improvements in attachment devices, and particularly to auxiliary means associated with a support, adapted to removably hold one member in cooperative relation to another. It is particularly adapted for use with the mouthpieces of sound-conveying conduits of "dictaphones," or the like, an object being to provide such a device which will securely hold a mouthpiece in place, and at the same 20 time, will permit it to be readily removed, and as readily attached.

It is customary with machines of the dictaphone type for several persons to use a single machine, each employing his own 25 mouthpiece, and because of the frequent insertion and removal of the mouthpiece—and in some cases, because of variation in their size, or in the size of their mounting—the attachment means would fail to properly secure the mouthpiece. Another object of the 30 invention, therefore, is to provide an attachment device which will not become deranged, or fail to function, because of repeated insertion and removal of the mouthpiece, and which will be compensating to 35 take care of variations in size, particularly of the mouthpieces.

A further object is to provide a device of this character which will be extremely simple in construction, and which may be used 40 in connection with attachment means, at present in use, without materially changing such means.

With the above and other objects in view, 45 an embodiment of the invention is shown in the accompanying drawings, and this embodiment will be hereinafter more fully described with reference thereto, and the invention pointed out in claims.

In the drawings—

Fig. 1 is a side view, partly in section, of the end of a sound-conduit, having a mouthpiece, and showing the attachment device according to the present invention;

Fig. 2 is a bottom plan view thereof; and 55

Fig. 3 is a detail perspective view of the spring clip employed, and which is representative of the essential feature of the device.

Similar reference numerals indicate corresponding parts throughout the several figures of the drawing.

Referring to the drawing, the sound-conduit illustrated is of the type employed in the commercial dictating machine, known as the "dictaphone," and is provided with a rigid tubular hand-grip 10, the main portion of the conduit (not shown) being flexible. At its extremity, there is formed an annular flared mouthpiece-receiving portion 13, having a plurality of slots, or cut-outs, 14, to provide resilient segments. An annular recess 15 is formed adjacent the base of the portion 13, so that the side wall of said portion 13 consists of a series of spaced 75 segments, each having an outwardly flared entering portion and a recessed retaining portion.

The mouthpiece 16, preferably of glass, is substantially bell-shaped, and is provided at its small end with an annular boss or bead 17 adapted to be pressed into the recess 15 of the portion 13, and whereby the mouthpiece is held in place.

A release spring clip 18, of substantially 80 wishbone or V-shape, but which could, of course, be made with one spring member, or with three or more, instead of two, is secured to the hand grip 10 by a screw 19, the head of which presses upon the clip in 85 a manner to tension it, so that its opposite end is constantly being pressed inwardly. The side portions are disposed beneath the bend of the handgrip 10, and are provided with hook-shaped ends 20 which extend 90 through two of the slots 14 of the portion 13, and into retaining relation with the bead 17 of the mouthpiece.

When using the device, in order to engage the mouthpiece with the portion 13, a 100 portion of the bead 17 is first engaged with in the hooked ends of the clip, whereupon the rest of the bead is pressed into the annular recess 15, the resilient segments of the portion 13 yielding sufficiently for this purpose.

It will be seen that the spring clip exerts 105 a pressure on the mouthpiece in a manner

to securely press and retain the bead 17 in the recess 15, even though it be of a diameter less than that of the recess.

While, for the purpose of describing the invention, the specific attaching means has been described with considerable particularity, and for only one of its many uses, it is not to be understood that the invention is limited to the specific means thus shown and described, since it will be apparent to those skilled in the art that such means may, if desired, be varied within wide limits, without departing from the invention being defined in the appended claims.

15. What is claimed, and for which Letters Patent of the United States is desired, is:

1. In combination, a member having a mouthpiece-receiving portion, a mouthpiece adapted to be engaged in said portion, and 20 spring means separate from the mouthpiece-receiving portion adapted to yieldably retain the mouthpiece therein.

2. In combination, a member having a mouthpiece-receiving portion, including resilient means adapted to yieldably retain a mouthpiece therein, a mouthpiece adapted to be engaged in said portion, and auxiliary resilient means adapted to cooperate with 25 said first resilient means to retain the mouthpiece in said portion.

3. In combination, a member having a mouth-piece-receiving portion, including an annular resilient means adapted to yieldably retain a mouthpiece therein, a tubular mouthpiece adapted to be engaged peripherally by said resilient means, and auxiliary 35 resilient means adapted to engage the mouthpiece at one point of its periphery and cooperate with said first resilient means to retain the mouthpiece in said portion.

4. In combination, a member having a mouthpiece-receiving portion, comprising a plurality of annularly arranged spaced resilient sections, each having a recessed retaining part and a resilient flared guiding part, a mouthpiece engaged in said portion and including an annular bead adapted to be 45 guided by said guiding part into engagement with said retaining part, and auxiliary retaining means secured to said member and extending into the space between two of 50 said adjacent resilient sections and adapted to engage said bead.

5. In combination, a member having a mouthpiece-receiving portion, comprising a plurality of annularly arranged spaced resilient sections, each having a recessed retaining part and a resilient flared guiding part, a mouthpiece engaged in said portion 55 and including an annular bead adapted to

be guided by said guiding part into engagement with said retaining part, and a spring clip of substantially V-shape secured at its bight to the member, and having its ends engaged in spaces between said resilient sections and engaging the bead of the mouthpiece.

6. In combination, a member having a mouthpiece-receiving portion, comprising a plurality of annularly arranged spaced resilient sections, each having a recessed retaining part and a resilient flared guiding part, a mouthpiece engaged in said portion and including an annular bead adapted to be guided by said guiding part into engagement with said retaining part, and a spring clip of substantially V-shape, and having hook-shaped ends, said clip being secured at its bight to the member, and having its hook ends engaged in spaces between said resilient sections and engaging the bead of the mouthpiece.

7. In combination, a member having a mouthpiece-receiving portion, comprising a plurality of annularly arranged spaced resilient sections, each having a recessed retaining part and a resilient flared guiding part, a mouthpiece engaged in said portion and including an annular bead adapted to be guided by said guiding part into engagement with said retaining part, a spring clip of substantially V-shape, a headed screw adapted to secure said clip at its bight to the member, and to tension said clip by pressure of the head of said screw thereon, 85 the ends of the clip being engaged in spaces between said resilient sections and engaging the bead of the mouthpiece.

8. In combination, a member having a mouthpiece-receiving portion provided with an annular recess, a mouthpiece including an annular bead adapted to be engaged in said recess, and yieldable means adapted to engage said mouthpiece to retain said bead in engagement with said recess.

9. In combination, a speaking-tube having a mouthpiece-receiving socket, an annular portion on the socket, a mouthpiece in the annular portion, resilient tongues extending from the annular portion into engagement with the mouthpiece to yieldingly retain the mouthpiece in the socket, and a wire clip having hook-shaped portions for engaging the mouthpiece in the socket.

Signed at 1819 Broadway, New York city, in the county of New York and State of New York, this 14th day of December, 115 A. D. 1922.

HENRY P. ROBERTS.
